UNITED STATES PATENT OFFICE.

CERF ROSENTHAL AND HUBERT MCL. ARMISTEAD, OF SAN FRANCISCO, CALIFORNIA,
ASSIGNORS OF ONE-HALF TO J. W. GUIBERSON AND J. C. SPERRY.

DOORCHECK.

Application filed June 22, 1927. Serial No. 200,584.

Our invention relates to that class of door-checks in which the restrictive circulation of a confined fluid serves as a yielding resistance to the closing of the door.

5 Our invention consists essentially in a yielding resistance member, and a presser member in position to make and break contact with the resistance member by the closing and opening respectively of the door. In its best 10 form, the resistance member comprises a novel assembly of a barrel, a reciprocative piston, and a confined circulating liquid body; and the presser member is a stud adapted to operate the piston. The general object of our 15 invention is to provide a simple, cheap and efficient door check having special advantages which will hereinafter be fully pointed out in connection with the following description of its structure and operation.

20 In the accompanying drawings, we have illustrated our door-check in its preferred form, it being understood that changes may be made in structure, form and arrangement without departing from the spirit of the invention as defined in the claims hereunto appended.

25 In the drawings, Fig. 1 is a view of our device in which the presser member is in elevation and the resistance member is in longitudinal section, taken on the line 1—1 of Fig. 2, the two members being separated in position ready to operate.

Fig. 2 is a longitudinal section taken on the line 2—2 of Fig. 3.

30 Fig. 3 is a sectional view taken in the same plane as that of Fig. 1, but showing the two members in position at the completion of their operation.

Fig. 4 is a section on the line 4—4 of Fig. 1.

40 Fig. 5 is a section on the line 5—5 of Fig. 1.

Fig. 6 is a horizontal section indicating the closed relation of the door and door frame, with the members of the door check indicated in plan.

45 Figs. 7 and 8 are fragmentary sectional views showing a modification, in which there is substituted for the spring to return the piston, an automatic coupling adapted to return said piston and to make and break connection therewith.

50 1 is a barrel having its rear end closed and its front end open. Fitted in the front end of the barrel is an annular nipple 2, the inner end of which forms a stop, defining the limit 55 of the return stroke of the piston. The pis-

ton as a whole comprises what may be termed the plunger proper indicated by 3 and the stem portion marked 4. The plunger 3 reciprocates within the bore of the barrel 1 and the stem 4 reciprocates within the bore of the nipple 2, both portions being properly fitted and packed, as shown at 5. The plunger 3 has a through port 6, the outer end of which is fitted with a check valve 7 in the form of a ball, and opens directly into a cross port 8 formed in the stem 4 at its junction with the plunger 3.

60 In the wall of the barrel 1 is a by-pass 9 which leads from the inner end of the barrel towards its front end, and there opens inwardly through notches 10 formed in the inner end of the stop nipple 2 and communicates with the interior or bore of the barrel 1 around the stem 4. A screw valve 11 seated in the barrel and accessible from the exterior 65 controls the capacity of the by-pass 9. Associated with the barrel 1, preferably formed therewith, is a member 12 which from its function may be termed an overflow chamber. It communicates with the cross port 8 of the stem 4 through a port 13, Fig. 4, and in its top it has an air vent 12', Figs. 1 and 3. In the bore of the barrel 1 at its inner end are formed relief 70 passages in the form of depressions 14 in the bore wall.

75 A spring 15 is fitted within the plunger 3 and bears upon the closed end of the barrel 1 and upon the plunger. This spring is best made tapering so that under compression it will nest itself in small compass. The stem 4 is hollowed out at 16 for lightness and is fitted 80 with a cap 16' on its outer end. 17 is a plate which carries the barrel 1 and its associated parts, and by which it is secured either to the door or to the door frame here shown, for illustration, as fitted to the door frame 18 in a 85 suitable mortise therein, Figs. 2 and 3. 19 is a presser stud adapted by its conical shape for easy contact with the cap 16' of the stem 4, and to readily enter the front end of the barrel. The stud has a plate 20 by which it is 90 secured in opposing relation to the barrel 1, either to the door frame or to the door as the case may be, here shown, for illustration, as fitted to the door 21, Figs. 2 and 3.

95 A fluid, preferably oil, indicated by 22, is 100 confined within the barrel 1 and its overflow chamber 12. The operation is as follows: As the door 21 closes under whatever impulse it may receive, say, for example, a spring, the stud 19 contacts with the cap 16' of the stem 105 110

4 and presses said stem and its plunger 3 inward. The check valve 7 closes and the spring 15 condenses on this stroke of the piston. The oil in the inner end of the barrel is forced through the by-pass 9, and, passing through the cross port 8, enters the overflow chamber 12 through the port 13, the air escaping through the vent 12'. The resistance offered by the circulating oil checks the initial and normally increasing impetus of the closing door, until, when this impetus, on account of the nearness of the door to its closed position is of no consideration as far as the noise of slamming is concerned, and is in fact essential to overcome the resistance of the latch, the plunger 3 has reached the relief passages 14, and passing along them, opens communication with both sides, and thereby relieves the pressure just as the door is about to close, so that this final act is devoid of resistance and takes place with certainty and without slamming.

As the door is opened and the stud 19 withdraws from the cap 16' of the stem 4, the spring 15 moves the plunger 3 outward, its return stroke, being limited by contact with the notched inner end of the nipple 2, Fig. 2. Upon this stroke, the check valve 7 opens, and the oil returns from the chamber 12 through the port 13 and around the piston stem and through the stem port 8, and piston port 6 to fill the inner end of the barrel, and thus re-establish the normal conditions. By adjusting the screw valve 11, the device may be readily adapted for whatever degree of resistance may be required of it. It will also be seen that the construction and arrangement of the double-portioned piston, provides for a thorough packing of the entire piston, and also furnishes by reason of the nipple 2, both a cylinder bore for the piston stem and a stop for defining the limit of the return stroke of the plunger. It will also be noted that the overflow chamber 12 avoids the necessity of an accurately established volume of oil, and by reason of its surplus, provides for less attention to compensate for evaporation and possible leakage. Also, that by equalizing the pressure, due to the passages 14, the door is relieved from the checking influence at the time when it should be removed, namely just as the door is about to close. It will also be noted that due to the air vented overflow chamber 12, the liquid body is at all times under atmospheric pressure, thus avoiding the liability of leakage and consequent attention to packing such as would be necessary if said body were under higher pressure.

In Figs. 7 and 8 we have shown a modification in respect to the means for returning the piston. Instead of a spring such as has been disclosed hereinabove, we may use an automatic coupling between the presser stud and the stem of the piston. This coupling may be of any suitable form adapted for auto-

matic connection as the door closes, and automatic release after the door is opening has pulled forward the piston to its limit. The form of coupling here shown comprises the interengaging jaws 23 and 24 and the trip 25.

Concerning the air-vented overflow chamber 12, it should be pointed out that such a chamber is only necessary in case the volume of oil content be too great for the capacity of the barrel 1 on the stem side of the piston. It is quite apparent, therefore, that if the oil used be reduced in volume to the capacity of the barrel-space on said side and said space be air-vented, just as the overflow chamber is vented, said chamber is not required, since on the forward stroke of the piston the air in front acts as a shock-absorber and the checking oil is fully taken care of in said stem side space. This is in fact what happens even when the vented overflow chamber is present, since said chamber may be regarded as part of the space on the stem side of the piston, and sufficient in capacity to take care of all of the oil even though the latter, as shown in Fig. 1, entirely fills the space in front of the piston.

We claim:

1. A door-check comprising a barrel having a restrictive by-pass connecting its end portions and having also an air vented overflow chamber for a fluid content; a ported, valve-controlled piston fitted within said barrel adapted by its reciprocation to circulate said fluid content; a presser member in position upon the closing of the door to contact with said piston and press it in; and a spring within the barrel for returning said piston upon the opening of the door.

2. A door-check comprising a barrel having a restrictive by-pass connecting its end portions; and an air vented overflow chamber for a fluid content; an annular nipple fitted in the outer end of the barrel; a reciprocative piston for circulating said fluid content, said piston comprising a ported valve controlled plunger portion and a stem portion of smaller diameter, said plunger and stem being fitted for reciprocation within said barrel and nipple, respectively, the inner end of the nipple functioning as a stop to limit the return stroke of the piston by contact with its plunger portion, and said stem portion having a port placing the outer end of the by-pass, the overflow chamber and the ported plunger in communication; a presser member in position, on closing the door, to contact with the stem portion of the piston and press it in; and means for returning said piston upon opening the door.

3. A door-check comprising a barrel having a restrictive by-pass connecting its end portions; and an air vented overflow chamber for a fluid content; an annular nipple fitted in the outer end of the barrel; a reciprocative piston for circulating said fluid content, said

5 piston comprising a ported valve controlled plunger portion and a stem portion of smaller diameter, said plunger and stem being fitted for reciprocation within said barrel and nipple, respectively, the inner end of the nipple functioning as a stop to limit the return stroke of the piston by contact with its plunger portion, and said stem portion having a port placing the outer end of the by-pass, the 10 overflow chamber and the ported plunger in communication, said barrel having in its inner end portion relief passages for equalizing fluid pressure on each side of the plunger as it approaches the limit of its inward stroke; 15 a presser member in position, on closing the door, to contact with the stem portion of the piston and press it in; and means for returning said piston upon opening the door.

4. A door-check comprising a barrel having a by-pass connecting its end portions, one of said end portions being closed, and the other air vented; a ported, valve-controlled piston fitted within said barrel adapted by its reciprocation to circulate a fluid content; 25 and a presser member in position to make and break pressure contact with said piston upon the closing and opening movements, respectively, of the door.

5. A door check comprising a barrel having one closed end and the other end vented to the atmosphere; a restrictive conduit connecting the end portions of said barrel; a valve controlled relief conduit connecting said end portions for fluid flow in one direction; and a piston in said barrel adapted by 30 its movement to circulate a fluid content of the barrel through said conduits.

6. A door check comprising a barrel adapted to contain a fluid and having one closed 40 end and the other end vented to the atmosphere; a piston operable in said barrel to circulate said fluid; and means connecting the end portions of said barrel and adapted to provide restricted fluid flow in one direction 45 and relatively free flow in the other.

7. A door check comprising a barrel adapted to contain a fluid; a piston operable in said barrel to circulate said fluid; means connect-

ing the end portions of said barrel and adapted to provide restricted fluid flow in one direction and relatively free flow in the other; and a reservoir communicating with said barrel for containing a supply of said fluid. 50

8. A door check comprising a barrel adapted to contain a fluid and having one closed 55 end and the other vented to the atmosphere; a piston operable in said barrel to circulate said fluid; means connecting the end portions of said barrel and adapted to provide restricted fluid flow in one direction and relatively free flow in the other; a presser member adapted for contact with said piston to move it in the direction of restricted fluid flow; and a spring for moving said piston 60 in the opposite direction. 65

9. A door check comprising a barrel adapted to contain a fluid; a piston operable therein to circulate said fluid; means connecting the end portions of said barrel and adapted to provide restricted fluid flow in one direction 70 and relatively free flow in the other; a reservoir communicating with said barrel for containing a supply of said fluid; a presser member adapted for separable contact with said piston to move it in the direction of restricted fluid flow; and a spring for moving said piston 75 in the opposite direction.

10. A door check comprising a casing having greater height than width and adapted for insertion in a door frame, said casing having a horizontally disposed barrel and a reservoir substantially in vertical alignment therewith; a piston operable in said barrel; means connecting the end portions of said barrel and adapted to provide restricted fluid 80 flow in one direction and relatively free flow in the other; a presser member adapted to be carried by the door for separable contact with said piston to move it in one direction; and means for moving said piston in the other 85 direction. 90

In testimony whereof we have signed our names to this specification.
